[57] CLAIM

The ornamental design for a pinch grip hanger, as shown and described.

DESCRIPTION

FIG. 1 illustrates a perspective view of the pinch grip hanger according to the design;

FIG. 2 illustrates a front view of the pinch grip hanger of FIG. 1;

FIG. 3 illustrates a cross-sectional view taken on line 3—3 of FIG. 2;

FIG. 4 illustrates a rear view of the pinch grip hanger of FIG. 1;

FIG. 5 illustrates a bottom view of the pinch grip hanger of FIG. 1;

FIG. 6 illustrates a right-hand side view of the pinch grip hanger of FIG. 1; and,

FIG. 7 illustrates a left-hand side view of the pinch grip hanger of FIG. 1.

The surface(s) or portion(s) of the article not shown in the drawing or described in the specification form(s) no part of the claimed design.
